(57) **CLAIM**

The ornamental design for a blanket, substantially as shown and described.

DESCRIPTION

FIG. 1 is a top, perspective view of the blanket; the view showing my new design;

FIG. 2 is a top, perspective view thereof;

FIG. 3 is a front view thereof;

FIG. 4 is a rear view thereof;

FIG. 5 is a side view thereof;

FIG. 6 is a side view thereof;

FIG. 7 is a top view thereof; and,

FIG. 8 is a bottom view thereof.

The cross-hatched shading is fragmentally shown for convenience of illustration, it being understood that the cross-hatched shading is uniformly continued over the surfaces on which it appears.
